UNITED STATES PATENT OFFICE

ELIZABETH MCGILL, OF WELLSVILLE, KANSAS

COPYHOLDER FOR TYPEWRITERS

Application filed May 8, 1929. Serial No. 361,401.

This invention relates to copy holders for typewriters.

The main object of the invention is to provide a copy holder having a stand on which is mounted a copy carrier which may be readily raised or lowered by the operator to bring any portion of the copy carried thereby into the view of the operator.

Another object is to provide a copy holder in a simple and durable form which may be folded into a small compass for convenient transportation from place to place or for storing away when not in use.

The foregoing and other objects together with means whereby the same may be carried into effect will best be understood from the following description of a preferred embodiment of the invention taken in connection with the accompanying drawings wherein:

20 Figure 1 is a front view of the invention ready for use.

Figure 2 is a side view thereof also ready for use.

Figure 3 is a view of the copy carrier 25 folded.

Figure 4 is a view of the supporting stand folded.

Figure 5 is a detail of the operating shaft.

Figure 6 is an enlarged section along the 30 line 6—6 in Figure 1.

Figure 7 is an enlarged detail view of the upper end of the central member of the copy carrier.

Figure 8 is a rear detail view of the rule 35 joint hinge between the connecting links and the rear leg.

The stand 1 comprises the two front legs 2 and 3 of any suitable material and the relatively longer rear leg 4. A supporting arm 5 is secured by a rivet 6 adjacent the upper 40 end of the leg 2 at the rear thereof and this arm is bent rearwardly at 7 from the leg to form a pocket or cleft 8. A similar supporting arm 9 is pivoted by a rivet 10 adjacent the upper end of the other leg 3 and is also bent rearwardly at 11 to form a similar pocket or cleft 12. These supporting arms 5 and 9 extend upwardly from the corresponding legs 2 and 3 but the arm 9 may 45 be swung inwardly to facilitate setting up

the device as will be set forth. Outer connecting links 13 and 14 are pivotally attached at 15 to the upper ends of the arms 5 and 9 and similar inner connecting links 16 and 17 are pivotally connected at 18 to the inner ends of the links 13 and 14, the inner ends of the said inner links 16 and 17 being pivotally connected by rivets 19 in an angle hinge 20 which has one of its webs 21 overlying these inner pivoted ends to form a rule joint and prevent the said links from pivoting except in one direction. The upper end of the rear leg 4 is reduced and flattened at 22 and is pivoted between pivot members 23 which are mounted upon the rivets 19 connecting the said inner links 16 and 17 so that the said leg 4 may be swung rearwardly from the front legs 2 and 3 and hold the same upright as shown. Lower links 24 and 25 are pivotally connected by rivets 26 to the rear of the front legs 2 and 3 near their lower ends and the inner ends of the said links are pivotally connected by rivets 27 in the angle hinge 28 which is similar in construction and purpose to the aforesaid angle hinge 20. A 75 rear leg connecting link 29 is pivoted at one end between pivot members 30 connected to the rivets 27 and at its other end is pivoted at 31 to the rear leg 4 to limit the rearward swing thereof. Elongated side bars 32 are secured at their upper ends over the supporting arms 5 and 9 by the mounting rivets 6 and 10 thereof and are similarly secured at their lower ends over the ends of the links 24 and 25 by their mounting rivets 26, the 85 said side bars 32 being thus spaced rearwardly from the legs 2 and 3 forming a slideway 33 for a purpose to be described. Operating rod mounting plates 34 and 35 which are angular in cross section are secured by rivets 90 36 through their narrow webs 37 to the upper ends of the legs 2 and 3 with their wide webs 38 directed rearwardly alongside the said legs as shown. Apertures 39 are provided in these wide webs 38 in horizontal alignment 95 with each other and in registry with the clefts 8 and 12 for a purpose to be described.

The copy carrier or rack 40 comprises the base members 41 and 42 having rear flanges 43 and 44 the outer ends of which are ex- 100

tended laterally and bent rearwardly and outwardly to form ears 45 which are slidably mounted in the slideways 33. The inner ends of the flanges 43 and 44 are pivotally attached by rivets 46 to the lower end of the center rack bar 47. Side rack arms 48 are pivoted by rivets 49 to the flanges 43 and 44 at either side of the center bar 47 and connecting arms 50 are pivoted at 51 to this bar 47 adjacent its upper end and at 52 to the side arms 48. In this manner a rack or carrier is formed upon which the copy may be placed and supported, the side arms 48 and connecting arms 50 preventing the copy from sagging and holding it flat as will be understood.

An operating shaft 53 is provided, the same being substantially longer than the width of the stand 1 and having one end 20 threaded at 54 for the reception of the operating knob 55. The shaft 53 is provided with a ratchet wheel 56 adjacent its end and a toothed operating wheel 57 medially located as shown. When the stand and carrier are 25 assembled the shaft 53 has its ends rotatably mounted through the apertures 39 in the plates 34 and 35, the leg 3 being cut away at 58 along its outside adjacent the web 38 of the plate 35 for the reception of the ratchet 30 wheel 56. The center rack bar 47 is provided with a plurality of spaced, aligned apertures 59 which the teeth upon the operating wheel 57 engage so that by turning the knob 55 and consequently the shaft 53 the carrier 40 35 may be raised or lowered at will as will be understood. The carrier 40 is held in proper engagement with the operating wheel 57 by a fixed side bar 60 secured to the rear of the center rack bar 47 at one side of the center 40 thereof and a movable side bar 61 which is pivoted upon one of the rivets 46 and is normally held in spaced aligned relationship with the bar 61 by a latch 62 pivoted at 63. The said side bars 60 and 61 are adapted to 45 lie along either side of the operating wheel 57 and as shown these bars are spaced rearwardly from the said center rack bar for the passage of the operating shaft 53. By raising the latch 62 the movable side bar 61 50 may be swung to one side so that the shaft 53 may be withdrawn from engagement with the carrier 40 as will be understood. In order to prevent the carrier 40 from falling of its own weight when it has been raised a 55 pawl 64 is pivoted at 66 in a slot 67 in the web 37 of the mounting plate 35, the inner or rear end of this pawl being aligned with the ratchet wheel 56 and normally held in engagement therewith by a coil spring 68. 60 Figures 3 and 4 clearly show the manner of folding the stand and note carrier 40. When setting the device up the stand and carrier are first unfolded and pivoted supporting arm 9 is swung inwardly so that the upper 65 ends of the legs 2 and 3 are spread apart.

The operating shaft 53 is then mounted on the carrier by means of the side bars 60 and 61 as set forth. The carrier is then slipped downwardly on the stand with the ears 45 in the slideways 33 until the ends of the operating shaft 53 are in alignment with the apertures 39, it being understood that the knob 55 is removed in the process of mounting the said shaft in place. By swinging the arm 9 back to its vertical position the upper ends of the legs 2 and 3 will be drawn together so that the ends of the operating shaft 53 project through the apertures 39 and the knob 55 is replaced completing the assembly.

While I have herein set forth a certain preferred embodiment of my invention it is understood it may vary from the same in minor structural details, not departing from the spirit of the invention and within the scope of the appended claims.

I claim:

1. In a device of the character described, a stand comprising foldably connected front legs having slideways, a rear leg foldably connected to the said front legs, an operating shaft operatively associated with the said front legs, a copy carrier slidably mounted in the said slideways and means upon the said operating shaft to engage the said copy carrier whereby the same may be raised or lowered.

2. In a device of the character described, a stand comprising a pair of foldably connected front legs and a single rear leg foldably connected to the said front legs, mounting plates upon the upper ends of the front legs, the said front legs having slideways, an operating shaft removably journaled through the said mounting plates, a toothed operating wheel upon the said operating shaft, a foldable note carrier slidably mounted in the said slideways the said note carrier having a plurality of apertures to receive the teeth of the said operating wheel.

3. In a device of the character described, a stand comprising a pair of front legs and a rear leg, a plurality of pivotally connected links connecting the said front and rear legs, bars secured to and spaced from the said front legs forming slideways, mounting plates secured to the upper ends of the front legs, a spring set pawl operatively mounted in one of the said mounting plates, a note carrier comprising a vertical center bar, base members pivoted to the lower end of the center bar, ears extended from the base members and adapted to play in the said slideways, side bars and connecting bars pivotally connected together and to the said base members and center bar, the said center bar having a plurality of longitudinally aligned and spaced apertures, a fixed side bar upon the rear of and spaced from the center bar, a similar side bar pivoted upon the said center bar, a latch adapted to normally hold the

said pivoted bar closed in alignment with
and spaced from the said fixed side bar, an
operating shaft adapted to be detachably
mounted through the said mounting plates
and the fixed and pivoted side bars, a knob
5 detachably mounted upon one end of the
operating shaft, a ratchet wheel upon the
other end of the shaft adapted to be engaged
by the said pawl, and a toothed operating
wheel upon the shaft adapted to turn be-
10 tween the said fixed and pivoted side bars in
engagement with the said apertures in the
said center bar.

In testimony whereof I affix my signature.

15 -- ELIZABETH McGILL.
